UNITED STATES PATENT OFFICE.

ORSON M. LEISHMAN, OF BAKER, OREGON.

LOAD-SECURING MEANS FOR FREIGHT-CARS.

1,392,343.

Specification of Letters Patent.

Patented Oct. 4, 1921.

Application filed September 30, 1920. Serial No. 413,840.

To all whom it may concern:

Be it known that I, ORSON M. LEISHMAN, a citizen of the United States, residing at Baker, in the county of Baker, State of Oregon, have invented a new and useful Load - Securing Means for Freight - Cars; and I do hereby declare the following to be a full, clear, and exact description of the invention, such as will enable others skilled in the art to which it appertains to make and use the same.

The invention relates to securing chains used in connection with flat cars on which logs and the like are shipped and has for its object to provide a device of this character comprising brackets pivotally connected to the opposite sides of the car, said brackets having their upper ends provided with detachable pins, to one of which pins is pivotally connected one end of a load securing chain, which chain is adapted to pass over the load and have its other end detachably connected to the upper end of the oppositely pivoted bracket. Also to provide the brackets with removable pins whereby the chain at both of its ends may be released as desired.

A further object is to provide inwardly and downwardly extending detachable stay chains, said stay chains extending downwardly from the upper end of the pivoted brackets and having their lower ends detachably connected in links carried by the car flooring.

35 A further object is to provide means and so construct the brackets that by removing the pins of the brackets the brackets and load holding chains will be released.

With the above and other objects in view the invention resides in the combination and arrangement of parts as hereinafter set forth, shown in the drawings, described and claimed, it being understood that changes in the precise embodiment of the invention 45 may be made within the scope of what is claimed without departing from the spirit of the invention.

In the drawings:

Figure 1 is a side elevation of a portion 50 of a conventional form of flat car, showing the invention applied thereto.

Fig. 2 is an end view of a conventional form of flat car showing the holding device applied thereto.

55 Fig. 3 is a perspective view of one of the pivoted brackets.

Fig. 4 is an enlarged top plan view of one of the grab links.

Referring to the drawings, the numeral 1 designates a conventional form of flat car, which flat car is provided with longitudinal sills 2 and transversely disposed sills 3, there being stakes 4 for holding a load, said stakes being of conventional form. The load holding chains are adapted to pass over the logs 5 and hold said logs against displacement. By referring to the drawings, it will be seen that only one chain is shown, however, it is to be understood that any number of chains may be used according to the type of car to which the device is applied. Secured to the ends of the sill 3 as at 6 are brackets 7, each of which brackets comprises the side members 8, the upper ends of which are connected together by a U-shaped member 9 which is welded or otherwise secured to the members 8 and forms means for stiffening the bracket. Extending transversely through apertures 10 of each bracket is a removable pin 11, said pin being provided with an eye 12 in which eye the hook 13 of the eye bolt removing chain 14 is hooked when it is desired to remove the pin and release the chains. The ends of the pins 11 are provided with cotter pins 15 which are removed before the pins are removed, said cotter pins forming means for preventing displacement of the pins 11. The brackets 7 are pivotally mounted on the bolts 6 and are adapted to swing outwardly and downwardly against the sides of the car when not in use. When it is desired to secure the load on the car, the pin 11 is removed sufficiently to allow said pin to pass through the apertured plate 16 carried by one end of the load holding chain 17 and the apertured plate 18 carried by one end of one of the stay chains 19. Stay chains 19 incline downwardly and inwardly and have their free ends disposed in grab links 20 carried by eye bolts 21 which pass through the flooring of the car. Chain 17 has its free end passed over the load as clearly shown in Fig. 2 and passed through a grab link 16^a which grab link is carried by an apertured plate 16^b through which the other pin 10 passes.

It will be seen that a load securing chain is provided, which is positive in its operation and one which may be easily and quickly placed in position or removed, however it is obvious that slight variations in the struc-

ture may be necessary according to slight variations in car construction.

The invention having been set forth what is claimed as new and useful is:—

- 5 The combination with a flat car, of a load holding device therefor, said load holding device comprising pivoted brackets pivoted to opposite sides of the car, said pivoted brackets being pivotally connected to the car at their lower ends, removable pins carried by the pivoted brackets adjacent their free ends, stay chains detachably connected to the pins and extending inwardly and downwardly and having their free ends de-
- 10

tachably connected to the car flooring, and 15 a load holding chain having one of its ends detachably connected to one of the pins and passing over the load and having its other end detachably connected to the removable pin of the pivoted bracket at the other side 20 of the car.

In testimony whereof I have signed my name to this specification in the presence of two subscribing witnesses.

ORSON M. LEISHMAN.

Witnesses:

JOSEPH M. DAVIS,
A. S. HIGGS.
